TUBE FLANGING TOOL

Robert D. McIntosh, River Forest, Ill., assignor
to The Imperial Brass Manufacturing Co., Chi-
cago, Ill., a corporation of Illinois

Application February 28, 1938, Serial No. 193,045

5 Claims. (Cl. 153—79)

My invention relates to tools and particularly to hand operated tools for forming flares, flanges, or beads of various styles on ductile tubing. Among the objects of my invention is the provision of a new and improved tool for forming flanges on tubes of more uniformly precise dimensions than heretofore were possible.

Another object is the provision of a new and improved tool for forming flanges of precise dimensions on tubing wherein the maximum outside diameter of the flange will be held to an extremely small tolerance.

Still another object is the provision of a new and improved tool for forming successive flanges of exact dimension wherein the length of the flanged end of tubing from inside end of the flange to the free end is maintained uniformly precise.

A further object is the provision of a tube flaring tool for forming flares having exact dimensions wherein means is provided for expanding a tube positioned approximately in the device into a flare having a precise maximum outside diameter and length, and wherein the wall thickness of the flared portion is maintained substantially the same as the original wall thickness of the tube.

A further object is the provision of a tube flanging tool adapted simultaneously to hold a tube and guide a saw in cutting the tube to a precise length so that when the flanging member is forced into the tool, the flanging operation will produce a flare of an exact predetermined length and diameter.

A still further object is the provision of a tube flanging tool for raising on ductile tubes bead-like flanges of precise dimensions located at uniform distances inward from the ends, there being provided a cut-off guide in the tool and the cut-off operation guided automatically so that the tube will have the proper length, in order to produce a flanged end of the desired dimension.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

50 Figure 1 is a perspective view of the preferred form of my device.

Figure 2 is an enlarged view of the clamping member in opened position.

55 Figure 3 is a view taken on the line 3—3 of Figure 1 drawn to a larger scale.

Figure 4 is a cross sectional view taken on the line 4—4 of Figure 1 drawn to a larger scale.

Figure 5 is a flanged section of tubing.

Figure 6 is a modified form of the clamping member in opened position.

Figure 7 is a cross sectional view of the modified form showing the tool assembled prior to the flanging operation.

Figure 8 is a cross sectional view similar to Figure 7 showing the tool after the flanging operation is completed.

Figure 9 is a section of tubing showing a modified form of a flange.

While the invention is susceptible of various modifications and alternative constructions, it is shown herein and will be described hereinafter in a preferred embodiment together with a modification. However, it is not intended that the invention is to be limited thereby to the specific constructions disclosed, but it is intended to cover all modifications and alternative constructions falling within the spirit and scope of the invention as defined by the appended claims.

In the design of flanging and flaring tools in the past, little regard was had for the exact dimensions of a flange, the precise size being left largely to the judgment of the mechanic making up the joint. As a result it has often happened that flanges either too larger or too small have been used and, as a result, improper joints have frequently been made up which, in the course of time, have become loosened or have leaked.

Since commercial coupling members or fittings are all made by machines, the formation of a flange upon the tubing to be used with them introduces the only element into a joint which is not uniformly machine-made at the factory, and by reason of the fact that it must be made by hand a lack of uniformity renders it, on the average, the weakest part of the joint. In order, therefore, to provide a manually operated tool which is capable of making flanges uniformly productive of a tight, leakless joint, such a tool must be constructed so as to hold the size of the flanges to a very small tolerance.

In the preferred embodiment of my invention chosen to describe the principles herein set forth, there is shown a clamping member indicated generally by the numeral 10 and a group of anvil members or flanging heads, indicated generally by the numeral 11. The clamping member is designed to receive and clamp tubes of several sizes in a position such that they may be cut

off to a proper length and a flange, flare or bead as the case may be, formed at the severed end.

The clamping member is composed properly of a pair of bars or elements 13 and 14. In the bar 13 are elongated recesses 15, 16 and 17 of different sizes in order to accommodate tubes of correspondingly different sizes and in the bar 14 are complementary recesses 15', 16' and 17' which cooperate with the recesses in the bar 13 10 when the clamping member is in closed position to form corresponding tube receiving openings.

At the left ends of the openings, as viewed in Figures 2, 3 and 4, each tube receiving opening is widened into enlarged portions 18, 19 and 20 15 suitable for forming flanges or flares at the end of corresponding sections of tubing. The enlarged portion 19 is shown in greater detail in Figures 3 and 4 and comprises a frusto-conical section 21 and a cylindrical section 22 concentric with the axis of the conical section joining it at the base. The frusto-conical section determines the shape and angle of the flare while the cylindrical section limits the maximum outside diameter of the widest portion of a flare which will become more fully apparent from the 25 description following.

The recessed bars 13 and 14 are held together by a pair of bolts 23 and 24 pivoted upon the ends of the bar 13 at the points 25 and 26 and 30 retained in assembled position in suitable slots in the bar 14 by means of wing nuts 27 and 28.

Adjacent one face of the clamping member, on the left as viewed in Figures 2, 3 and 4 there is positioned a block 30, corresponding in length 35 to the length of the bars 13 and 14 and having a thickness approximately equal to the combined thickness of the bars 13 and 14. This block 30 is secured to the bar 13 by means of screws 31 and 32 holding it rigidly thereto but spaced from 40 the bar 13 by means of a relatively thin sheet of somewhat softer metal 33. It will be noted that this sheet of soft material is positioned only at the lower part of the bar 13 thereby causing a slit or groove 34 to be formed between face 35 of the block and adjacent face 36 of the upper 45 bar 14. The purpose of this slit or groove is to provide a guide for a saw, indicated diagrammatically by the numeral 37 in Figure 1, the saw being for use in cutting off tubing to the proper 50 length. Since, as is customary in the tool art, wearing parts of the tool are made of tool or other hard varieties of steel and it is therefore desirable to have a soft metal bottom for the saw groove in order that when a saw passes 55 through a section of tube and comes to rest in the bottom of the groove, the teeth will not be dulled or damaged. By this arrangement, a relatively soft pad is supplied for the sharp and delicate saw teeth without sacrificing in any way the 60 rugged make up of the tool.

This tool is designed especially to form a flange or flare 28' in a length of ductile tubing 29, of a precise length and having an outside diameter which never exceeds a predetermined amount. 65 Such flares are necessary in order to assure uniformly tight joints when used with the conventional type of coupling or fitting. In order then to assure the formation of such a precise flare it is necessary that the exposed portion of tubing 70 29 which is to be expanded in order to form the flange or flare 28' should be of a precisely accurate length. While this could be done by pushing the end of a length of tubing end into the clamping member so that the end would be exactly 75 flush with the face at which the flaring oper-

ation takes place, it is not a practical procedure and the man on the job would seldom if ever take such care to have the flanges made uniform. Especially where a tool is to be operated in places where accurate positioning becomes inconvenient or when a flare is to be made in a hurry, it is not reasonable to expect a mechanic to exercise any more care than just enough to satisfy the job. Not only is it inconvenient but often it is impossible to take the necessary care to adjust every tube in a clamping member in just the same way. In order, therefore, to provide for a quick, ready and automatic positioning of a flare in a clamping member, the applicant has designed a tool which provides a cut-off operation operative on an arbitrary length of tube to reduce it to exactly the right length. In order that this may be possible, the frusto-conical section 21 and cylindrical section 22 previously described together with an additional recess 40 are 20 made to aggregate a depth equal to that shown by the dimension 41 and this dimension determines precisely the desired length of tubing which will be expanded into a flange or flare. (See Figure 4.) 25

In operation therefore a length of tubing is clamped between the bars of the tube clamping member with the end protruding slightly toward the left as viewed in Figure 2. The bars are then secured tightly in place and the tube is sawed 30 off by means of a saw 37 which will be guided to cut the tube to the precise length desired as shown by the dot and dash line in Figure 2. Although it may appear that the exposed length of tubing is slightly greater than the sloping length 35 of the frusto-conical section it is to be borne in mind that when a tube of a given diameter is flanged outward into a flare, whose outside diameter is almost double that of the tube, the ductile tube material comprising it will be considerably 40 shortened and will then neatly occupy a shorter space such as that provided for it in the tool.

Block 30 completely overlies the tube receiving openings 15, 16 and 17 and has in it a series of apertures 45, 46 and 47 of uniform diameter, one 45 concentric with each of the tube receiving openings. Cooperable with the clamping member 10 is the group of anvils 11 comprising individual members or flanging heads 48, 49 and 50 having uniform diameters and each provided with a 50 flanging or flaring cone designed to fit the particular tube with which it is to be used. For convenience the anvils are swiveled on a rod 52 so that any one of the group may be used as desired. 55

The anvil 49 has a flaring cone 51 adapted to cooperate with the tube receiving opening 16 and the tube clamped therein. The flaring cone has substantially the same angle of flare as the frusto-conical section in the bars 13 and 14. In 60 order to assure the precise formation of a flare, a shoulder such as 53 is formed at the working end of the anvil which abuts the bottom of the recessed portion 40 and limits the distance which the flaring cone can enter the corresponding 65 frusto-conical section. Also at the working end of the anvil, the edge 54 is beveled over in order to guide the flaring cone into the recessed portion to properly finish the flaring operation.

The steps therefore in making a precise flare 70 with this tool consists first of inserting a length of tubing in the clamping member and securely fastening it in place by clamping the bars together with the screws and wing nuts, next sawing off a section of the tube so that the remain- 75

ing portion has exactly the right length, and finally inserting a suitable anvil into its corresponding aperture in the block 10 and driving it home by means of a hammer or other suitable instrument so that the flaring cone enters the free end of the tubing, flares it outward to an amount exactly flush with the cylindrical section 22 thereby limiting the maximum dimensions of the flare. When the anvil is driven in the shoulder 53 abuts against the adjacent portions of the clamping member and prevents the flaring cone from thinning out the metal comprising the flare thereby retaining this automatically sized flare or flange at a thickness corresponding to the original thickness of the wall of the tubing.

A modified type of flange or flare is shown in Figure 9 and is what is frequently termed a bead. The production of a flange or beaded end upon a tube of precise dimension incorporates the same principle of operation as that described for the frusto-conical flare but necessitates a structure slightly different in detail.

Figure 6 shows a clamping member comprising a pair of bars 60 and 61 in which is a series of tube receiving openings 62, 63 and 64 terminating at the left hand end respectively in enlarged portions 65, 66 and 67. The bars are designed to fit one upon the other and are positioned exactly in alignment by means of the projections 68 and 69 in the bar 61 which extend into apertures 70 and 71 of the bar 60. The bars are held in place one upon the other by means of screws 72 insertable through the apertures 73 in the upper bar and secured in the tapped holes 74 in the lower bar.

Securely attached to the left face of the lower bar 61 is a block 75 secured thereto by means of screws 76. This block has suitable apertures 77, 78 and 79 positioned respectively opposite the tube receiving openings 62, 63 and 64. The block is spaced from the clamping member by means of a soft metal sheet 80 which provides a saw guide 81 between the block and the clamping member. In this embodiment a tube 85 is shown positioned in the tool where it can be sawed to a proper length by means of a saw blade which may be inserted in the guiding groove 81. An anvil 86 is provided which has a diameter slightly smaller than the aperture 78 and the enlarged portion 66 of the tube receiving opening. The anvil is provided with a central recess 87 of a diameter sized to snugly accommodate the exposed end of the tubing 85 receiving it to a depth slightly less than the length of tube exposed within the enlarged portion 66. There is an annular enlarged portion 88 at the open end of the central recess having a diameter of a dimension which will determine a desirable maximum outside diameter for a flange or bead 89 to be formed on the tubing. Similarly the exact length 90 of the flanged or beaded end of the tubing is determined precisely by the depth of the central recess 87 beneath a face 91 at the working end of the anvil 86. Recess 87 also forms a rounded end 91.

In operation a length of tubing 85 is clamped between the bars 60 and 61 and sawed off by means of a saw blade inserted in the slot 81. Then an anvil such as 86 which has a form similar to the anvil 47 described in the preferred embodiment is inserted in the aperture 78 and extends through into the enlarged portion 66 of the clamping member. During the operation, the cut end of the tube 85 enters the central

recess 87 of the anvil and abuts against the bottom as shown in Figure 7. The anvil is then struck with a hammer or squeezed by some means to drive the face 91 against the bottom of the enlarged portion 66 which thereby limits the drive of the anvil into the enlarged portion of the clamping member. During operation the cut end of the tube is compressed longitudinally and since the area of least resistance is at the outward wall, the bead 89 is forced outwardly of the tube into the space provided by the annular enlargement 88. Since the walls of the enlargement are positively fixed, the outward maximum diameter of the bead 89 is limited to a precise dimension, as is also the length indicated by the numeral 90. The tool is therefore operative to form any number of absolutely uniform flanged or beaded ends for tubing of any size for which the tube is designed.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim:

1. In a flaring tool adapted for use with a cutting blade and including a flaring anvil, a pair of complementarily recessed clamping bars for holding a length of tubing having a flaring recess at one end, a block having an aperture corresponding to the recess for reception of the flaring anvil bolted to one of said bars with the aperture in alignment with said recess, and a sheet of relatively soft material positioned between a portion of the block and a portion of said one bar providing a gasket over a portion of the space therebetween to permit securely bolting the parts together leaving a slot between the block and the other bar at the portion not filled by the sheet adapted to receive the cutting blade for cutting off the tubing to a length suitable for making a flare.

2. In a tool for cutting and flanging tubing a clamping member including separable bars having complementary halves of a tube receiving opening formed therein, said opening having an enlarged portion at one end of the opening comprising portions of flange forming elements, a block rigidly attached to one of said bars having openings in axial alignment with the tube receiving openings, a sheet of soft metal positioned between a portion of the face of said block and a portion of the adjacent face of said one bar and separating the remaining portions of the faces of said block and said bar by a space equal to the thickness of said sheet thereby providing a guide for a blade-like instrument, said sheet being simultaneously adapted to form a soft stop for said blade-like instrument thereby minimizing damage to the edge thereof, and a flaring anvil positionable by the openings in said block in tube flanging relation with said enlarged portion adapted to be pressed against the tube to form a flange.

3. In a tube cutting and beading tool, a clamping member including a pair of separable elements provided with complementary recesses forming a tube receiving opening, said opening having an enlarged portion at one end having a depth equal to the length of tube necessary to form a complete beaded end, a block attached to said member in partially separated relation to form a slit providing a guide for a blade-like tool

- for cutting off a length of tube exposed in the enlarged portion at a plane flush with the end of said portion, said block having an aperture in axial alignment with said enlarged portion, and an anvil adapted to fit slidably into said aperture and said enlarged portion, said anvil having a central recess for receiving the tube end for a portion of its exposed length, said recess being formed with an annular enlargement at the open end to accommodate a raised bead and limit its outside diameter, and a shoulder in the bottom of said recess, adapted when the anvil is forced into said aperture and said enlarged portion of the clamping member to determine the length of the beaded end of the tube.
4. In a tool for cutting and flanging tubing adapted for use with a cutting blade and including a tube flanging member, a pair of complementary recessed clamping bars for holding a length of tubing having an enlarged aperture at the end of said recess to receive said tube flanging member, a block having an aperture corresponding to the recess for reception of the tube flanging member bolted to one of said bars with the aperture in alignment with said recess, and a sheet of relatively soft material positioned between a portion of the block and a portion of said one bar providing a gasket over a portion of the space therebetween to permit securely bolting the parts together leaving a slot between the block and the other bar at the portion not filled by the sheet adapted to receive a cutting blade for cutting off the tubing at a length suitable for working said tubing.
5. In a tool for cutting and flanging tubing, adapted for use with a cutting blade and including a tube flanging member, a pair of superimposed complementary recessed clamping bars, for holding a length of tubing, having an enlarged aperture at the end of said recess to receive said tube flanging member, and a block-like extension having one end rigidly connected to the end of the lower portion of the lower bar, below said enlarged aperture, the other portion of said end of the block-like extension being disposed in close spaced apart relation to the end of the upper portion of said lower bar and the corresponding end of the upper bar to define a slot extending perpendicularly to the axis of the aperture and open at the top and sides for receiving and guiding a cutting blade for cutting the tubing to a desired length, said block extension having an aperture corresponding to and aligned with said aperture in the clamping bars for the reception and guidance of said tube flanging member into cooperating relation with the clamping bars.

ROBERT D. McINTOSH.
